UNITED STATES PATENT OFFICE

JAMES E. GUNTER AND JOHN STEWART, OF ANDERSON, SOUTH CAROLINA

OIL PAN FOR COILER GEARS

Application filed March 8, 1932. Serial No. 597,575.

This invention relates to drip pans for cotton drawing frames or cotton revolving flat cards and has for the primary object, the provision of a device of the above stated character especially adapted to prevent lubricant of the coiler gear from soiling and rendering the cotton sliver unfit for use during its passage through the coiler gear into the sliver container.

Another object of this invention is the provision of a pan having means for securing the same to the coiler gear so as to rotate therewith and collect the waste lubricant from the coiler gear and thereby prevent the usual lubricant drippings from engaging the sliver.

With these and other objects in view, this invention consists in certain novel features of construction, combination and arrangement of parts to be hereinafter more fully described and claimed.

For a complete understanding of our invention, reference is to be had to the following description and accompanying drawings, in which

Figure 1 is a fragmentary vertical sectional view illustrating a cotton drawing frame with a drip pan connected to the coiler gear thereof and constructed in accordance with our invention.

Figure 2 is a side elevation illustrating the drip pan.

Figure 3 is a top plan view illustrating the same.

Referring in detail to the drawing, the numeral 1 indicates a fragmentary portion of a cotton drawing frame having the usual feed rollers 2 for discharging cotton sliver into the chute 3 of a rotating coiler gear 4.

The coiler gear 4 is rotated by a pinion 5 meshing with teeth on the periphery thereof and is rotatably supported by a plate 6 on the drawing frame 1 by having a groove 7 receiving a flange 8 formed on the coiler gear. The coiler gear also having a groove 9 receiving a flange 10 on the plate 6. Lubricant is fed into the groove 7 in any suitable manner for the purpose of lubricating the coiler gear during its rotation and by actual experience it has been found that the

lubricant overflows the groove 7 and drips downwardly, being caught by the sliver cotton within the sliver container 11 thereby ruining or soiling the sliver and rendering the same unfit for use and to overcome this disadvantage our invention is applied to the coiler gear as shown in Figure 1 and consists of a circular pan 12 having an upstanding marginal flange 13. Stud bolts 14 are carried by the pan and extend through apertures in the coiler gear and receive thereon nuts 15 whereby the pan is supported to the coiler gear and directly under the same for the purpose of catching the lubricant drippings from the groove 7. Bosses 16 are formed on the pan 12 with the bolts extending therefrom for the purpose of forming stops to properly position the pan relative to the coiler gear and plate 6 of the drawing frame whereby the pan is free to rotate with the coiler gear and will not interfere with the operation of the machine permitting the usual upward movement of the coiler gear by the accumulated sliver within the container 11 for actuating the conventional type of trip lever for stopping the operation of the drawing machine when the container is filled with sliver.

The pan 12 is provided with an opening 17 aligning with the discharge end of the chute 13 and is surrounded by a marginal flange 18 terminating in close proximity to the discharge end of the chute so that the sliver discharging from the chute may pass through the pan without coming in contact with the lubricant caught therein. It being understood that the sliver passing through the opening 17 enters the container 11 and is placed therein in coiled formation by the rotation of the sliver gear.

While we have shown and described the preferred embodiment of our invention, it will be understood that minor changes in construction, combination and arrangement of parts may be made without departing from the spirit and scope of our invention, as claimed.

Having thus described our invention, what we claim is:

1. In combination with a cotton drawing

- frame having a rotating coiler gear for delivering the sliver into a container, and means between the gear and container to catch lubricant dripping from said gear and 5 adapted to permit free passage of the sliver to the container from the coiler gear without soiling by the lubricant.
2. In combination with a cotton drawing frame having a rotating coiler gear for delivering the sliver into a container, means 10 between the gear and container to catch lubricant dripping from said gear, and means whereby the sliver from said gear may pass through the first named means without coming in contact with the lubricant caught thereby.
3. In combination with a cotton drawing frame having a rotating coiler gear for delivering the sliver into a container, a drip 15 pan secured to said gear and located between the latter and the container for catching lubricant dripping from the gear, and means in said pan to permit sliver to pass therethrough from the gear to the container 20 without coming in contact with lubricant caught in said pan.
4. In combination with a cotton drawing frame having a rotating coiler gear provided 25 with a chute and a container disposed thereunder, a pan carried by said gear between the latter and the container for catching lubricant drippings from the gear, said pan having an opening to permit the sliver from the chute to pass therethrough into the container 30 without contacting with the lubricant caught by said pan.
5. In combination with a cotton drawing frame having a rotating coiler gear provided 35 with a chute and a container disposed thereunder, a pan carried by said gear between the latter and the container for catching lubricant drippings from the gear and having an opening, and a flange formed on the pan about said opening and aligning with 40 the discharge end of the chute to permit the sliver to pass through the pan without coming in contact with the lubricant caught in the pan.
6. In combination with a cotton drawing frame having a rotating coiler gear provided 45 with a chute and a container disposed thereunder, a pan carried by said gear between the latter and the container for catching lubricant drippings from the gear and having an opening, and a flange formed on the pan about said opening and aligning with the discharge end of the chute to permit the sliver to pass through the pan without coming in contact with the lubricant caught in 50 the pan, said pan of a diameter greater than the diameter of the gear.
7. In combination with a cotton drawing frame having a rotating coiler gear for delivering the sliver into a container, a flanged 55 pan located between the gear and the con- 60
- tainer, means detachably securing the pan to the gear for rotation therewith, said pan adapted to catch lubricant drippings from the gear, and means in the pan for permitting the sliver from the gear to pass therethrough into the container without coming in contact with the lubricant caught in said pan.
- In testimony whereof we affix our signatures.
